UNITED STATES PATENT OFFICE.

BENJAMIN BASSKIN, OF ST. LOUIS, MISSOURI.

TROUSERS.

Application filed March 12, 1925. Serial No. 14,879.

This invention relates to trousers, and more particularly to the button-hole flies therefor.

In the ordinary trousers as now made the 5 button-hole fly consists of a piece of cloth which is usually lined and contains the button-holes, and this piece is simply tacked at spaced points between the button-holes to the front edge of the trousers cloth and 10 along the opening.

In the formation of such a button-hole fly, a piece of lining is first seamed to the trousers cloth along the opening and turned back and pressed. The piece forming the 15 button-hole fly is faced with a lining which is applied to the cloth of the fly by stitching the piece and lining inside out, turning and pressing and attaching the piece and its lining by a cover-seam along the edges.

20 After the button-holes are formed in this piece and lining, the fly is laid along the edge of the trousers opening and tacked thereto at points between the button-holes.

The piece, its attached lining and the lining 25 piece on the trousers cloth are then turned back on the inside face of the trousers cloth and attached thereto by a seam running along the fly. The process is not only laborious and not only requires skilled operators

30 in order to properly locate the fly, but the construction is also objectionable due to the fact that when the trousers are being worn, the buttons and lining of the fly are liable to become exposed, presenting an 35 unsightly appearance.

One of the objects of this invention, therefore, is to provide a button-hole fly in which a piece containing the button-holes is so attached to the trousers as to form a button 40 receiving pocket which is entirely closed along the edge of the trousers opening so as to entirely conceal the buttons and the lining.

Another object is to provide a novel process 45 whereby the attachment and formation of the fly may be more readily and quickly performed and by unskilled operators.

Further objects will appear from the detail description taken in connection with the 50 accompanying drawing, in which:

Figure 1 is a front view of a trousers embodying this invention;

Figure 2 is a detail showing the fly partly attached;

Figure 3 is a section on the line 3—3, 55 Figure 2;

Figure 4 is an inside view showing the fly fully attached;

Figure 5 is a section on the line 5—5, 60 Figure 4; and

Figure 6 is a section on the line 6—6, 65 Figure 4, the fabric layers being spaced apart to show the construction.

Referring to the accompanying drawing, the trousers as shown may be of any usual 65 or suitable construction and may be formed in the usual manner, except in the attachment of the button-hole fly, as hereinafter described. This button-hole fly consists of a piece 1 of cloth of the same pattern as 70 the trousers cloth 2. Attached to this piece 1 is a lining 3 and formed in the piece and lining are button-holes 4, while the outer edges of the piece and lining are secured together by a cover-seam 5; the piece and 75 lining thus form an integral unit. A piece of lining 6 may also be provided. The piece 1 and its lining 3 containing the button-holes 4 are now placed against the outer 80 face of the trousers cloth 2 while the lining piece 6 when employed, is placed against the inner face, with the edges in alinement along the front edge of the trousers cloth and along the trousers opening. A continuous line of stitches 7 is then run along the 85 alined edges so as to seam all the pieces together as shown in Figures 2 and 3, the pieces in Figure 2 being only shown partially together so as to illustrate the operation;

in practice, however, the seam is not only run along the edge of the trousers opening but also along the top edge and through the waist-band 8 which is placed at this point between the lining piece 6 and the lining piece 3. The piece 1 and lining piece 3 are now turned against the 90 inside face of the trousers and against the lining piece 6, the fold being at 9 on the trousers cloth so that the fold 10 of the piece 4 is slightly inside and back of the 95 fold 9. A line of stitches 11 is now run along the inner edge of the piece 1 and through this piece, the lining 3, the lining 6 and the trousers cloth 2 and at the top also through the band 8. Preferably the 100 top button-hole 12 is formed after the parts are attached so as to pass through all the thicknesses of cloth as shown in Figure 1

in order to receive the top button 13. A button 14 may also be attached to the inside of the fly as shown in Figure 4 in order to cooperate with the usual button-hole on the other side of the trousers as usual.

There is thus provided trousers in which the fly is attached to the trousers by a continuous line of stitches 7 in order to provide a pocket 15 which is entirely closed along the edge of the trousers opening so as to receive the buttons 16 on the other half of the trousers. These buttons will, therefore, always be concealed so as to not become exposed even if the trousers front is under tension. Moreover no lining will be exposed since the piece 10 is of the same pattern as the trousers cloth. The edge of the trousers opening will more over always present a neat appearance, especially since the seam 7 is fully covered and since the folded edge 9 overhangs the folded edge 10 of the piece 1. Moreover it will readily be seen that the formation of the fly and its attachment is such that no accurate locating is necessary so that the operations can be performed by comparatively unskilled operators. Moreover the operations are considerably reduced in number so that the cost will be considerably lessened.

It is obvious that various changes may be made in details without departing from the spirit of this invention; it is, therefore, to be understood that this invention is not to be limited to the specific details shown and described.

Having thus described the invention, what is claimed is:

1. A button-hole fly for trousers comprising, a separate piece of cloth containing button-holes and attached by a continuous line of stitches along and to the front edge of the trousers cloth, said piece being turned back against the inside face of the trousers cloth and secured thereto along its inner

edge by a continuous line of stitches in order 45 to form a button-receiving pocket which is entirely closed along the edge of the trousers opening.

2. A button-hole fly for trousers comprising, a separate piece of cloth containing button-holes and attached by a continuous line of stitches along and to the top and front edges of the trousers cloth, said piece being turned back against the inside face of the trousers cloth and secured thereto along its inner edge by a continuous line of 50 stitches in order to form a button-receiving pocket which is entirely closed along the edge of the trousers opening.

3. A button-hole fly for trousers comprising, a separate piece of cloth and lining containing button-holes and attached by a continuous line of stitches along and to the front edge of the trousers cloth, said piece and lining being turned back against the 55 inside face of the trousers cloth and secured thereto along its inner edge by a continuous line of stitches in order to form a button-receiving pocket which is entirely closed along the edge of the trousers opening.

4. In the art of making trousers, the process comprising placing a piece of cloth and lining containing button-holes against the outer face of the trousers cloth with the lining outside and with the edges of the 75 piece and lining along the edge of the trousers opening, placing another piece of lining against the inner face of the trousers cloth and along the trousers opening, stitching along the aligned edges of the pieces of 80 cloth and lining and trousers, turning the attached piece and its lining along the seam against the other lining piece and securing the same.

In testimony whereof I affix my signature 85 this 6th day of February, 1925.

BENJAMIN BASSKIN.
